UNITED STATES PATENT OFFICE.

GIULIO MARCHETTI, OF HALIFAX, ENGLAND, ASSIGNOR TO ARNOLD,
CONSTABLE & CO., OF NEW YORK, N. Y.

DESIGN FOR CARPET.

SPECIFICATION forming part of Design No. 25,465, dated May 5, 1896.

Application filed February 28, 1896. Serial No. 582,013. Term of patent 3½ years.

To all whom it may concern:

Be it known that I, GIULIO MARCHETTI, a subject of the Queen of Great Britain, residing at Halifax, county of York, England, have invented and produced a new and original Design for Carpet, of which the following is a specification, reference being had to the accompanying drawing, making a part of the same, and is sufficient to enable others skilled in the art to make and use my invention.

What I claim as new, and desire to secure by Letters Patent, is—

In a design for a carpet, the body A, and border B, substantially as shown.

GIULIO MARCHETTI.
